(57) **CLAIM**

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; and, FIG. 7 is a front view thereof shown in an environment of use.

The portions of the garment shown in broken lines in FIGS. 1-7 do not form part of the claimed design. The broken line showing of the hands, legs, head, and torso in FIG. 7 is for the purpose of illustrating portions of the environmental structure and forms no part of the claimed design. The parallel line shading shown on the outer arm, upper front, and lower back portions of the garment in FIGS. 1-7 illustrates a contrast in appearance only and does not illustrate any particular tone, color, material, texture, pattern, or finish.
